UNITED STATES PATENT OFFICE.

CHARLES F. POPE, OF WATERBURY, CONNECTICUT, ASSIGNOR TO THE
WATERBURY MANUFACTURING COMPANY, OF SAME PLACE.

SCREW HOOK OR RING.

SPECIFICATION forming part of Letters Patent No. 223,079, dated February 5, 1884.

Application filed November 26, 1883. (No model.)

To all whom it may concern:

Be it known that I, CHARLES F. POPE, of Waterbury, in the county of New Haven and State of Connecticut, have invented a new Improvement in Screw Hooks or Rings; and I do hereby declare the following, when taken in connection with accompanying drawings and the letters of reference marked thereon, to be a full, clear, and exact description of the same, and which said drawings constitute part of this specification, and represent, in—

Figure 1, the screw-ring; Fig. 2, a screw-hook of like construction; Fig. 3, the screw detached; Fig. 4, the collar detached from the screw; Fig. 5, the screw and collar united; Fig. 6, the ring detached; Fig. 7, vertical section, and Fig. 8, top view, of the base detached; Fig. 9, the ring and base set together; Fig. 10, the ring and base united; Fig. 11, vertical section through the complete article.

This invention relates to an improvement in the construction of the hook or ring provided with a screw-shank, by which it may be secured at any desired point, with special reference to the ring or hook used to suspend smoke-bells from the ceiling of apartments over gas-burners, but applicable to other purposes. These rings or hooks have usually been made by forming a mold corresponding to the ring and base, then placing the head of a screw-shank within the base part of the same, and then pouring metal into the mold which forms the rings and base and surrounds the head of the screw-shank, so as to make a firm union therewith. If these articles are left as they come from the mold, they present a rough appearance; if finished, the labor for finishing the surface is so considerable as to make the article expensive.

The object of my invention is to form the hook and base from sheet metal, and so unite the parts with the screw as to make the article substantially as firm as if cast thereon; and the invention consists in the construction as hereinafter described, and more particularly recited in the claim.

The screw which I employ to form the shank is that usually employed, and is a common nicked-headed wood-screw, A. From sheet-metal I cut a collar, B, in diameter slightly

less than the diameter of the base to be produced. The perforation through this collar corresponds to the body of the screw, and is set thereon and secured by solder or otherwise close up to the head, as seen in Fig. 5. The ring 55 or hook C, I also cut from sheet metal, as seen in Fig. 6, forming radially-projecting shank a at one point, on the end of which is a tenon, b. The base D, I also strike up from sheet metal of cup-shape, having an opening, d, in 60 its center corresponding to the tenon b on the shank a. Around the edge of the base is a flange, e, the internal diameter of the flange corresponding to the collar B. The tenon b of the ring or hook is introduced through the 65 mortise in the base, as seen in Fig. 9, and is of a length so as to project a considerable distance into the base. The inner end of the tenon is cut concave. When thus inserted, with a suitable instrument, the tenon is upset, as seen in Fig. 10, so as to firmly attach the ring or hook to the base. The screw-head and collar B are then inserted within the base, and so that the flange e will project below the collar and the head of the screw come to a 70 bearing upon the inner end of the tenon, as seen in Fig. 11. When in that position, the flange e is closed down over the collar, as seen in Fig. 11, which securely unites the parts. By bringing the tenon to a solid bearing upon 75 the screw-head such an engagement is made between the tenon and the neck of the screw that the screw will be readily turned by the application of power to the ring itself. Again, it is frequently necessary to first start the 80 screw by means of a hammer. To do this the blows must be struck upon the ring itself, and were the shank of the ring not supported directly on the screw, such a blow would indent and deface the base. Therefore, by bringing the 85 screw and tenon together I accomplish this 90 double object.

I have described this invention as a hook or ring, and from the illustrations in Figs. 1 and 2 it will be seen that the only difference between the hook and ring is that the hook is made open at one side while the ring is closed.

The ring may be struck in dies to give it any desired ornamentation or shape—as, for instance, it may be desirable to make the ring 95 100

round in transverse section. Dies having a correspondingly-concave cavity will produce such a shape; but the configuration or shape of the ring is no part of my invention.

5 I claim—

As an article of manufacture, the herein-described screw hook or ring, consisting of the headed screw shank A, having the collar B secured to its body below the head, the cup-shaped base D struck from sheet metal, with a central opening, d, therein, the ring or hook struck from sheet metal, and constructed with a radially-projecting shank, a, having a tenon,

b, upon its end corresponding to the central opening in the base, the hook and base secured together by said tenon, the screw and collar introduced into the open end of the base to bring the screw-head to a bearing against the said tenon, and the flange or edge of the base closed down upon the collar on the screw, substantially as described.
